Term of patent 14 years

(Cl. D9—2)

To all whom it may concern:

Be it known, that I, Mario De J. Ortega, a citizen of the United States and residing at Asharoken Beach, Northport, Long Island, in the county of Suffolk, State of New York, have invented a new, original, and ornamental Design for a Combined Sponge Cleaner and Vacuum Squeegee Nozzle, of which the following is a specification, reference being had to the accompanying drawing, forming a part hereof, and in which,

Figure 1 is a front elevational view showing the combined sponge cleaner and vacuum squeegee nozzle, with its suction nozzle and squeegee portion lowermost, and with its sponge type cleaner portion uppermost.

Figure 2 is a right side elevational view of the device shown in Figure 1, with the lower lip of the squeegee portion of the nozzle lowermost.

Figure 3 is a bottom plan view of the device shown in Figure 1.

Figure 4 is an angularly inclined top plan view taken substantially on plane 4—4 of Figure 2.

I claim:

The ornamental design for a combined sponge cleaner and vacuum squeegee nozzle, substantially as shown.
